MARKING APPARATUS

Robert L. Barker, Petaluma, Calif.

Application June 1, 1956, Serial No. 588,781

7 Claims. (Cl. 101—35)

This invention relates generally to a marking apparatus and more particularly to a marking apparatus of the type adapted to be flush mounted in a horizontal working surface.

In cutting of meat in locker plants, it is generally desirable to separately wrap each piece of meat so that it can be readily removed from the other pieces of meat in the locker after the meat has been frozen. It is also generally desirable to mark the wrapping on each piece of meat with the type of meat, the name of the cut of the meat, the locker number, the date of wrapping the meat and other pertinent information. Devices or apparatus heretofore provided for marking the paper used for wrapping the meat have been very unsatisfactory.

In general, it is an object of the present invention to provide a marking apparatus which is particularly adapted for use in pre-marking wrapping paper in locker plants.

Another object of the invention is to provide a marking apparatus of the above character which can be flush mounted in a table top or other horizontal work surface.

Another object of the invention is to provide a marking apparatus of the above character which can be easily operated.

Another object of the invention is to provide a marking apparatus of the above character which is counterbalanced to facilitate easy operation.

Another object of the invention is to provide a marking apparatus of the above character which is self inking.

A further object of the invention is to provide a marking apparatus of the above character which is readily adjustable.

Additional objects and features of the invention will appear from the following description in which the preferred embodiment has been set forth in detail in conjunction with the accompanying drawing.

Referring to the drawings:

Figure 1 is a bottom plan view of a marking apparatus incorporating the features of the present invention.

Figure 2 is a cross sectional view taken along the line 2—2 of Figure 1.

Figure 3 is a view similar to Figure 2 with some of the parts removed showing the printing roller being pulled downwardly away from the inking pad.

Figure 4 is a view similar to Figure 3 but shows the inking pad removed from the printing aperture and the printing roller raised into the printing aperture.

Figure 5 is a cross sectional view taken along the line 5—5 of Figure 1.

Figure 6 is a cross sectional view taken along the line 6—6 of Figure 5.

As shown in the drawing, the marking apparatus is mounted on a table or other horizontal working surface 10. The apparatus consists of a framework 11 which is comprised of a horizontal base member 12 that is rabbeted into the upward surface of the work table 10. A pair of side wall members 13 and 14 are fixed to the hori-

2

zontal base member 12 by suitable means such as spot welding. A bottom member 16 is fixed to the lower ends of the side wall members 13 and 14 by suitable means such as spot welding.

5 A pair of arms 18 and 19 are pivotally connected to the side wall members 13 and 14 by suitable means such as the fastening assemblies 21. Each of the fastening assemblies 21 consists of a bolt 22 which is mounted in the side wall and extends through a spacer 23. The spacer 23 is provided with a reduced portion 24 which is adapted to receive the end of the associated arm 18 or 19. A nut 26 and a washer 27 secure the bolt 22 and the spacer 23 to the side wall. It will be noted that the depth of the reduced portion 24 is greater than the width of the arms 18 and 19 so that the arms can easily pivot about the spacer 23.

A printing rollers assembly 29 is mounted on the free ends of the arms 18 and 19 and consists of a plurality of printing rollers 31 loosely mounted on a shaft 32 for rotation about the shaft 32. The ends of the shaft 32 are threaded and extend through the free ends of the arms 18 and 19 and are fastened thereto by nuts 33. A flanged spacer 34 is mounted on the shaft 32 adjacent each of the arms 18 and 19. The printing rollers 31 are mounted between the spacers 34.

Each of the printing rollers 31 consists of a roller 36 of suitable material such as plastic. Indicia are provided on the roller by suitable means such as a strip or ring 37 of resilient material having raised indicia 38. 30 The strip is secured to the roller 36 by suitable means such as a clip 39 which engages the end portions of the strip and is fastened to the roller by screw 41. As shown in the drawing, the rollers 36 can be of various widths to accommodate indicia of various sizes.

35 One side of each of the rollers 31 is provided with a plurality of notches 43 which are adapted to be engaged by detents 44 carried by a spring-like member 46. A plurality of spring-like members 46 are provided and are mounted on the shaft 32 adjacent the notched sides of the rollers 31. Each of the spring-like members are provided with a slot 47 which engages an extension 48 of a U-shaped member 49 connecting the intermediate portions of the arms 18 and 19. The engagement prevents rotation of the spring-like members 46.

40 The printing rollers 31 and the spring-like members 46 are loosely mounted on the shaft 32 so that the printing rollers can be rotated manually when desired. The detents 44 serve to hold the printing rollers in the desired position.

45 The horizontal base member 12 of the framework 11 is provided with an elongate printing aperture 52 which has a length sufficient to receive the printing indicia from all of the printing rollers 31. It is of a width sufficient to receive one set of printing indicia from each of the printing rollers 31.

50 The printing roller assembly 29 is continuously urged towards the printing aperture 52 by spring means 53. The spring means 53 consists of a threaded rod 54 which depends from a bracket 56 fixed to the horizontal base member 12 by suitable means such as spot welding. The threaded rod 54 extends through an opening (not shown) in the U-shaped member 49 and through a spring 57 which is fixed to the rod by a wing nut 58.

An operating arm 61 is fixed to the U-shaped member 49 intermediate the arms 18 and 19. A roller bearing assembly 62 is mounted on the free end of the arm 61 and serves as a cam follower which engages a cam member 63. Cam member 63 is in the form of a casting which has a lower leg 64 journaled onto a rod 66 which has its ends fastened to the side wall members 13 and 14 by suitable means such as screws 67. A pair of collars 68 mounted on the rod 66 serve to prevent lateral

movement of the cam member 63 relative to the rod 66.

The cam member 63 is provided with two cam portions 69 and 71. Both portions lie in the same plane and are adapted to be engaged by the cam follower 62. Cam portion 71 is provided with four arcuate cam surfaces 71a, 71b, 71c and 71d for a purpose hereinafter described. Cam portion 69 overlies the arcuate cam surface 71b and is provided with cam surfaces 69a and 69b for purposes hereinafter described.

Cam member 63 is provided with an extension 73 which extends at right angles to the leg 64. One end of a connecting link 74 is fastened to the extension 73 by suitable means such as a screw 76 and the other end is connected to a block 77 by suitable means. For example, as shown in the drawing, the block is provided with a threaded extension 78 which extends through a hole (not shown) in the end of the link 74 and is fastened thereto by a nut 79.

The block 77 is mounted on a threaded rod 80 by nuts 81 mounted on each side of the block 77. The other end of the threaded rod 80 is connected to an operating handle or pusher bar 82 by screw 83 in a cylindrical extension 84 of the handle 82. The cylindrical extension 84 of the operating handle 82 is slidably mounted in a tubular member 86 which is provided with a cylindrical recess 87 adapted to receive the cylindrical extension 84. The tubular member 86 is an integral part of a face plate 88 which is mounted on the table 16 by suitable means such as screws 89. A spring 91 is connected between the block 77 and the tubular member 86 for a purpose hereinafter described.

Another spring 92 is connected between the bottom member 16 and one end of the cam portion 71 for a purpose hereinafter described.

An inking pad holder 96 normally closes the printing aperture 52 and carries an inking pad 97 which faces downwardly from the inking pad holder 96. A plurality of small holes (not shown) are provided in the inking pad holder 96 and are spaced across the length of the holder to provide means by which ink can be dropped onto the inking pad 97.

The inking pad holder 96 is carried by a platelike member 98 which is connected to a U-shaped member 99 by suitable means such as screws 101. The ends of the U-shaped member 99 are connected to side wall members 13 and 14 by fastening assemblies 102 similar to fastening assemblies 21 to permit pivotal movement of the U-shaped member 99 about the fastening assemblies 102.

An operating arm 103 is fastened to the U-shaped member 99. Its free end is provided with a roller bearing assembly 104 which serves as a cam follower and is adapted to be engaged by the lower cam surface 71d of cam member 63 for a purpose hereinafter described. A spring 106 is connected between the operating arm 103 and the top portion of cam member 63.

A spring 107 has one end connected to the U-shaped member 99 and 108 and has the other end connected to the side wall member 13 at 109. A similar spring 111 is connected to the U-shaped member 99 at 112 and to the side wall member 14 at 113. The springs 107 and 111 serve to urge the U-shaped member 99 in a clockwise direction into engagement with stops 114 of suitable resilient material such as rubber.

Operation of my marking device may now be described as follows: Let it be assumed that my marking apparatus has been installed in a locker plant in which custom work is done for the locker plant's customers. Let it also be assumed that it is desired to pre-mark the pieces of paper used for wrapping the meat. A sheet of wrapping paper to be used for wrapping is torn from a roll of paper and placed on the table or work surface 10 over the printing aperture 52. The operating handle 82 is then operated by the person moving his body against the handle. If desired, the operating handle can be

operated by one hand, however, it is generally more desirable to operate the handle 82 with the body by leaning against the handle so that both hands are free for handling the paper.

During initial movement of the handle 82, the printing roller assembly 29 is moved away from the inking pad holder 96 as shown in Figure 3. During this initial movement, cam member 63 is rotated clockwise from the position shown in Figure 2 until the cam follower 62 engages the cam portion 69. As clockwise movement of the cam member 63 is continued, the cam follower 62 is moved downwardly by the cam surface 69a. The cam follower 62 serves to lower the printing roller assembly 29 from the inking pad holder 96 to the position shown in Figure 3.

At about the time the cam follower 62 engages the lowermost portion of the cam surface 69a, the cam surface 71d of cam portion 71 engages the cam follower 104. Continued clockwise movement of cam member 63 by movement of the handle 82 causes clockwise rotation (as viewed in Figure 4) of the U-shaped member 99 to move the inking pad holder 96 away from the printing aperture 52.

At the same time that the inking pad holder is moved away from the printing aperture 52 the cam follower 62 comes into engagement with arcuate cam surface 71c which serves to raise the cam follower 62 which in turn moves the printing roller assembly 29 into the printing aperture 52 as shown in Figure 3. Thus, while the inking pad holder 96 is moved to an out-of-the-way position, the printing roller assembly 29 is moved to the printing position.

The operator then takes one of his hands while holding the sheet of paper with the other hand and wipes his hand across the portion of the sheet immediately above the portion of the printing roller assembly 29 projecting through the printing aperture 52. This causes the desired imprint to appear on the sheet of paper.

It is to be understood that the printing rollers 31 can be rotated by finger or pencil through the printing aperture 52 to set them in the desired position. The printing rollers can also contain various types of information. For example, one roller could contain the various types of meat such as pork, beef, etc. Another roller could contain the cuts of meat, another roller could contain the locker number, and still another could contain the date of wrapping.

As soon as the sheet of paper has been marked by wiping the hand across the same over the printing roller assembly 29, the operating handle 82 is released by the body and the marking apparatus snaps back to the position shown in Figure 2.

The various springs in the apparatus serve to return the apparatus to its normal or home position as shown in Figure 2. Springs 91, 107, 111, 92 and 57 are the primary springs for returning the apparatus to its normal position. The springs also serve as a counterbalance to facilitate easy operation of the apparatus. Spring 106 connected between the upper portion of the cam member 63 and the operating arm 103 moves with the cam member 63 and operating arm 103 and makes it easier to operate the apparatus.

It will be noted that when the apparatus is returning to its home or normal position from the position shown in Figure 4 that the cam member 63 moves in a counter-clockwise direction as viewed in Figure 4. The cam follower 62 first engages cam surface 69b which moves cam follower 62 downwardly which in turn moves the printing roller assembly 29 out of the printing aperture 52. At the same time, cam follower 104 moves towards the end of cam surface 71d to permit the inking pad holder 96 to gradually return to its home position. Movement of the cam member 63 continues in a counter-clockwise direction until the cam follower 62 engages cam surface 71a which serves to move the printing roller as-

sembly back into engagement with the inking pad 97. The spring 57 mounted on the rod 54 also serves to move the printing roller assembly into engagement with the inking pad 97.

Thus, it is apparent that each time the marking apparatus is operated, the marking indicia being used on the printing rollers come into contact with the inking pad 97 to insure that there is always sufficient ink on the indicia to give a good mark.

The position of the printing roller assembly 29 and the printing aperture 52 can be adjusted by shifting the block 77 on the threaded rod 80 by adjustment of the nuts 81.

After the sheet of paper has been marked by my marking apparatus, the piece of meat may be wrapped. The same operation is performed for wrapping the other pieces of meat. Whenever a different cut of meat is encountered, the position of the printing roller can be rapidly changed so that the proper indicia will appear through the printing aperture 52 merely by moving the desired roller in one direction or the other by a finger or pencil.

It will be evident from the foregoing that my invention is capable of a wide usefulness. In addition to its use in locker plants, it is apparent that it can be readily used in many packing and wrapping applications where pre-marking is desirable. The marking apparatus is particularly useful in that it can be operated by slight movement of the body leaving both hands free for packing and wrapping operations.

Although the invention has been disclosed as a manually operated device, it is apparent that it can be readily adapted for electrical operation by mounting an electrically operated solenoid on the framework for the apparatus which will move the link 74 in a manner similar to that in which it is moved by the operating handle 82.

This application is a continuation in part of my co-pending application Serial Number 493,995 filed on March 14, 1955, now abandoned.

I claim:

1. In a marking apparatus adapted to be mounted on a horizontal work supporting surface, a framework, one portion of said framework having an upper surface substantially flush with the horizontal work supporting surface, said upper surface being provided with a printing aperture, an inking pad holder mounted on said framework and movable between a position closing the printing aperture and an out-of-the-way position, an ink pad mounted in said inking pad holder and facing downwardly from said inking pad, a printing member mounted on said framework and movable between three positions, in a first position being in engagement with said inking pad, in a second position being out of engagement with said inking pad and in a third position being raised into the printing aperture, and means for operating said inking pad holder and said printing member whereby said printing member is first moved away from said inking pad and moved to its second position and said inking pad holder is moved to its out-of-the-way position while said printing member is raised to its third position in the printing aperture.

2. Marking apparatus as in claim 1 wherein the operating means includes an operating member adapted to be engaged by the trunk portion of the body to cause operation of the apparatus and at the same time permitting free use of the hands.

3. Marking apparatus as in claim 1 wherein the operating means includes a unitary cam member for causing movement of said inking pad holder and said printing member.

4. In a marking apparatus adapted to be mounted on a horizontal work supporting surface, a framework, one portion of said framework having an upper surface substantially flush with the horizontal work supporting

surface, said upper surface being provided with a printing aperture, an inking pad holder mounted on said framework and movable between a position closing the printing aperture and an out-of-the-way position, an ink pad mounted in said inking pad holder, a printing roller assembly mounted on said framework and movable between three positions, in a first position being in engagement with said inking pad, in a second position being removed from engagement with said inking pad, and in a third position being raised into a printing position in the printing aperture, and means for causing movement of said inking pad holder and said printing roller assembly whereby said printing roller assembly is first removed from engagement with said inking pad and moved to its second position and then to cause said inking pad holder to be moved to its out-of-the-way position while said printing roller assembly is moved to its first position.

5. Marking apparatus as in claim 4 wherein said printing roller assembly comprises a shaft, a plurality of rollers rotatably mounted on said shaft, raised indicia on said rollers adapted to be moved upwardly through said printing aperture, and detent means mounted on said shaft for retaining said rollers in predetermined angular positions.

6. Marking apparatus as in claim 4 together with means for adjustably positioning the printing roller assembly with respect to the printing aperture.

7. In a marking apparatus adapted to be mounted on a horizontal supporting surface, a framework, one portion of said framework having an upper surface substantially flush with the horizontal work supporting surface, said upper surface being provided with a printing aperture, an inking pad holder pivotally mounted on said framework and movable between a position closing the printing aperture and an out-of-the-way position, an ink pad mounted in said ink pad holder and facing away from the aperture when the pad holder is in a position closing the printing aperture, a printing member pivotally mounted on said framework and movable between three positions, in a first position being in engagement with said inking pad, in a second position being out of engagement with said inking pad and in a third position being raised into the printing aperture, and means for actuating said inking pad holder and said printing member whereby said printing member is first moved away from said inking pad and then said inking pad holder is moved to an out-of-the-way position and raising said printing member into the printing aperture, said last named means including a unitary cam member, a cam follower engaging the cam member and connected to said printing member, said cam member having three arcuate surfaces engaged by the cam follower to move the printing member between first, second and third positions as the cam member is moved, and a second cam follower connected to said inking pad holder, said cam member having a fourth arcuate surface engaged by the additional cam follower to move the inking pad holder from a position closing the printing aperture to an out-of-the-way position as the cam member is moved.
